GUN

Wiley T. Moore, U. S. Army, Wright Field, Ohio

Application May 7, 1935, Serial No. 20,300

8 Claims. (Cl. 42—78)

(Granted under the act of March 3, 1883, as amended April 30, 1928; 370 O. G. 757)

The invention described herein may be manufactured and used by or for the Government for governmental purposes, without the payment to me of any royalty thereon.

5 This invention relates to a gun and to a method of permanently reshaping a projectile passing through the gun, and is a continuation in part of abandoned application Serial No. 696,207 filed November 1, 1933.

10 From the standpoint of interior ballistics it is desirable to have a bullet which has little mass but great cross-sectional area and consequently low sectional density in order to give the powder gases a sufficient area upon which to push. From 15 the standpoint of exterior ballistics it is most desirable to have a bullet of the smallest cross-sectional area with the greatest sectional density.

The purpose of this invention is to provide a 20 gun barrel which is capable of permanently reshaping a specially formed bullet during its passage through the bore of the gun whereby the bullet may conform to the requirements of interior and exterior ballistics. As a consequence 25 higher muzzle velocities may be obtained with the same chamber pressures now employed in conventional weapons, or conversely, the same muzzle velocity may be obtained with lower developed pressures.

30 More specifically the invention consists in providing a gun barrel with rifling which not only serves to impart rotation to the bullet but which acts as a forming die to reshape a part of the bullet and reduce its cross-sectional area.

35 To these and other ends, the invention consists in the construction, arrangement and combination of elements described hereinafter and pointed out in the claims forming a part of this specification.

40 A practical embodiment of the invention is illustrated in the accompanying drawing, wherein:

Fig. 1 is a longitudinal sectional view of a gun barrel constructed in accordance with the invention.

45 Figs. 2, 3, 4, and 5 are sectional views on the respective lines of Fig. 1.

Fig. 6 is a longitudinal sectional view of a bullet before passing through the gun barrel.

50 Fig. 7 is a rear end view of Fig. 6.

Fig. 8 is a view in side elevation of the bullet after passing through the barrel.

Fig. 9 is a rear end view of Fig. 8.

55 Referring to Figs. 1 to 5, the gun barrel 5 has a bore in which lands 6 are gradually widened

from breech to muzzle and at the same time gradually converged towards the axis of bore at the muzzle with the result that the grooves 7 are gradually narrowed and deepened towards the muzzle. The twist of the rifling as shown is 5 only about one-half of a turn in the entire length of the barrel, the barrel being of the conventional length of 24 inches for .30 caliber ammunition, or 80 calibers in length.

A preferred form of bullet for use with the 10 gun barrel is shown in Figs. 6 to 9 and consists of a body 8 and an integral enlarged hollow base 9 constituting a cup-shaped tail approximately one-half as long as the body. The diameter of the rear end of the base 9 is approximately twice 15 the maximum diameter of the body.

The base 9 is formed with a hemi-spherical cavity 10 which is in communication with a cavity 11 provided axially in the rear portion of the body. The wall of the base is of a gradually 20 decreasing thickness from its front to its rear end.

The base 9 is composed of a metal which is 25 deformable and which may be permanently reshaped. The gun barrel constitutes a forming die which acts on the base to permanently reshape it providing fins 12 as shown in Figs. 8 and 9 and reducing the cross-sectional area of the base. During the travel of the bullet through the greater part of the gun barrel its body 8 is out 30 of contact with the bore. At the muzzle of the barrel the lands 6 are preferably dimensioned to slightly contact the body 8 and thereby give it lateral stability.

Approximate calculations of the interior ballistics of the bullet made in comparison with a conventional .30 caliber bullet are as follows; assuming bullets of the same weight and the same developed pressures. Where the diameter of the base 9 is twice that of the body 8, then the acceleration of the bullet will be four times that of the conventional .30 caliber bullet. Approximately the same amount of energy is consumed in reshaping the base 6 as is used in giving rotational movement to the .30 caliber bullet.

The particular form into which the base 6 is reshaped will depend on the nature and character of the lands and grooves of the gun barrel. While four lands and grooves have been shown it is obvious that the number may be varied and that 50 they may be arranged to produce different shapes of the fins 12. The fins may be formed with a curve so that in flight the bullet may literally screw itself through the air.

By reference to Figs. 2 to 5 it will be noted that 55

the diametral distance between the lands at the muzzle is approximately one-half the maximum diameter of bore and also approximately equal to the depth of a groove. The total convergence 5 for each land is approximately equal to one-fourth the maximum diameter of bore.

While the invention finds its most practical application for small arms the principles set forth are equally applicable to all classes of weapons 10 irrespective of their caliber.

I claim:

1. A gun barrel having a bore with lands and grooves, the lands being gradually widened from breech to muzzle and gradually converging to- 15 wards the axis of bore at the muzzle with a total convergence for each land approximately equal to one-fourth the maximum diameter of bore, the grooves being gradually narrowed and deepened towards the muzzle while retaining the maximum 20 diameter of bore, and the lands and grooves having a twist of approximately one-fourth to one- half of a turn in a barrel of approximately eighty calibers length.

2. A gun barrel having a bore with lands and 25 grooves, the lands being gradually widened from breech to muzzle and gradually converging to- wards the axis of bore at the muzzle, the grooves being gradually narrowed and deepened towards 30 the muzzle while retaining the maximum diameter of bore, and the lands and grooves having a twist of approximately one-fourth to one-half of a turn in a barrel of approximately eighty calibers length.

3. A gun barrel having a bore with lands gradu- 35 ally widened from breech to muzzle and gradu- ally converging towards the axis of bore at the muzzle with a total convergence for each land approximately equal to one-fourth the maximum diameter of bore, and the lands having a twist

of approximately one-fourth to one-half of a turn in a barrel of approximately eighty calibers length.

4. A gun barrel having a bore with lands gradu- 5 ally widened from breech to muzzle and gradu- ally converging towards the axis of bore at the muzzle, and the lands having a twist of approxi- mately one-fourth to one-half of a turn in a barrel of approximately eighty calibers length.

5. A gun barrel having a bore with lands gradu- 10 ally converging towards the axis of bore at the muzzle and with grooves having a constant dis- tance from the axis of bore and the lands having a twist of approximately one-fourth to one-half 15 of a turn in a barrel approximately eighty calibers length.

6. A gun barrel having a bore with lands and 20 grooves, the lands being gradually widened from breech to muzzle and gradually converged to- wards the axis of bore at the muzzle, and grooves 25 being resultingly narrowed and deepened towards the muzzle, and the diametral distance between the lands at the muzzle being approximately one- half the maximum diameter of bore.

7. A gun barrel having a bore with lands and 30 grooves, the lands being gradually widened from breech to muzzle and gradually converged to- wards the axis of bore at the muzzle, the grooves being resultingly narrowed and deepened towards the muzzle, and the diametral distance between the lands at the muzzle being approximately equal to the depth of a groove.

8. A gun barrel having a bore with lands gradu- 35 ally widened from breech to muzzle and gradu- ally converging towards the axis of bore at the muzzle with a total convergence for each land approximately equal to one-fourth the maximum diameter of bore.

WILEY T. MOORE.
